ROY THOMAS, OF LOS ANGELES, CALIFORNIA

TORCH

Application filed April 2, 1929. Serial No. 351,911.

This invention relates to that type of torch which produces intense heat through combustion by the aid of free oxygen of a gas containing either or both carbon and hydrogen, acetylene being the combustible gas generally employed and the inventor being therefore hereinafter described with particular reference to an oxyacetylene torch.

It is an object of the invention to so control flash-back in the torch as to eliminate all danger therefrom, and more particularly to provide a control which will function irrespective of the relative pressures of the oxygen and acetylene, and which comprises an extremely simple and readily manufactured construction requiring no replacement or adjustment.

It is a further object of the invention to provide a flash-back control which will also function to stabilize the flow of the gases which produce the combustible mixture, so as to insure proper combustion and a flame of maximum efficiency.

More particularly it is an object of the invention to provide an abrupt lateral offset in a supply bore which leads to the mixing chamber of the torch, so that in the event of flash-back beyond the mixing chamber and into said bore, the flame propagation by impinging squarely against the solid abutment surface formed by the lateral offset will rebound and be so retarded that the velocity of the gas being supplied through the bore to the mixing chamber will arrest further rearward travel of the flame, and will thus extinguish the fire through lack of the presence at said point in the supply bore in rear of the mixing chamber of the necessary combination of both oxygen and combustible gas for supporting combustion.

It is a further particular object of the invention to preferably arrange the lateral offset so as to form a restriction in the supply bore for stabilizing the flow of gas therethrough prior to its discharge into the mixing chamber, in order to insure a uniform combustible mixture and consequent maximum efficiency of combustion.

It is a still further object of the invention to preferably provide such a lateral offset in

rear of the mixing chamber in each of the oxygen and the acetylene supply bores, although only such offset in the acetylene bore is essential; and if said offsets are provided in both the acetylene and the oxygen bores they preferably each form an appreciable restriction for stabilizing both the oxygen and the combustible gas prior to their intermixing for forming the combustible mixture.

Further objects of the invention will be readily understood from the following description of the accompanying drawing, in which:

Fig. 1 is a side elevation, partly in axial section, of a torch constructed in accordance with the invention.

Fig. 2 is a detail fragmentary transverse section on the line 2-2 of Fig. 1.

Fig. 3 is a detail side elevation, partly in axial section, of a head for a torch embodying the invention and showing a modified construction.

Fig. 4 is a detail fragmentary transverse section on the line 4-4 of Fig. 3.

Fig. 5 is a view similar to Fig. 3 but showing a still further modification.

Fig. 6 is a detail fragmentary transverse section on the line 6-6 of Fig. 5.

The invention may be embodied in any torch adapted to burn a combustible mixture of a gas such as acetylene and an oxidizing agent such as pure oxygen; and is herein described in connection with a usual oxyacetylene welding torch wherein a head 1 has supply bores 2 and 3 for acetylene and oxygen respectively, and a mixer 4 which is mounted on the head and is adapted to form a combustible mixture of the oxygen and acetylene, with the combustible mixture adapted to pass through a usual gooseneck 5 to a burner tip 6.

Acetylene and oxygen are preferably respectively supplied to bores 2-3 through tubes 7 and 7' which are suitably fixed to the rear end of head 1 and may be enclosed in a handle 8, and the acetylene and oxygen supply are separately regulated by usual valves 9 and 9' for the respective tubes 7 and 7'.

In the event of flash-back, if the flame travels rearwardly beyond mixer 4 it enters bores 2 and 3 which are so arranged as to arrest

rearward propagation of the flame and thus extinguish the fire through absence in either of said bores of the necessary mixture of acetylene and oxygen for supporting combustion, and this arrangement of the bores whereby flame propagation is arrested preferably also provides for restricting the bores so that the gases traveling therethrough to the mixer 4 will be stabilized as a result of passing said restrictions, in order to insure a uniform mixture in the chamber 4.

As an instance of this arrangement the acetylene bore 2 has an abrupt lateral offset forming an abutment shoulder at substantially right angles to the axis of the bore and adapted for impingement by flame traveling rearwardly through said bore, so that the impact of the flame against the non-yielding abutment will cause its rebound and so arrest its travel that the velocity of the rearwardly traveling flame will be exceeded by that of the acetylene being supplied in the opposite direction through the bore, and the flame will thus be arrested at the lateral offset in the bore and will consequently be extinguished through the absence in said bore of the oxygen necessary to support combustion. The oxygen bore 3 is shown as provided with a similar lateral offset for arresting flame propagation, although the arresting of rearward travel of the flame through the acetylene bore 2 is that which is essential for eliminating dangerous consequences from flash-back.

The lateral offsets in bores 2 and 3 may be provided as shown in Figs. 1 and 2, wherein the major lengths of said bores are drilled straight into head 1 from its rear end and at the desired inclination for alinement of the discharge ends of said bores with the mixer 4, and said discharge ends of the bores 2-3 which are shown at 10-11, respectively, are drilled into head 1 from its front end, with the bores 2-10 and 3-11 of preferably the same diameter and having parallel but non-concentric axes whereby said bores 2-10 and 3-11 do not concentrically aline but partially overlap so as to form right-angled solid abutment shoulders 12-13 projecting into bores 10 and 11 where they meet the bores 2 and 3.

Flame propagation traveling rearwardly through bores 10 and 11 will thus forcibly strike the abutments 12-13 and will be subjected to a shearing action when tending to follow the abrupt lateral offsets and enter the major lengths of the bores 2-3, and the flame will thus be arrested so that the velocity of the acetylene and oxygen being supplied through bores 2-3 respectively, will prevent further rearward travel of the fire which will consequently be extinguished in the respective bores through the presence in each of the same of only one of the component elements, acetylene and oxygen, the mixture of which is necessary to support combustion.

The same result may be accomplished by the modified construction shown in Figs. 3 and 4, wherein head 1^a is provided with an oxygen bore 3 which may have a laterally offset discharge end 11 as previously described; and the major length of the acetylene bore comprises a plurality of restricted bores 2^a in close juxtaposition and communicating at their rear ends with the acetylene supply tube 7 as previously described, with a bore 10^a drilled into the front end of head 1^a so as to form the acetylene discharge to the mixer, and having its axis parallel to those of bores 2^a and concentric with the medial point between the said bores 2^a, and being of a diameter whereby its cross-sectional area will completely overlie the cross-sectional areas of the plurality of bores 2^a as shown in Fig. 4. Flame traveling rearwardly through bore 10^a will thus strike the abutment shoulder 12^a which is formed by the reduced cross-sectional areas of bores 2^a, and the flame will thus be arrested and its path of travel will be subjected to abrupt lateral offset and a shearing action as previously described.

A still further modification for accomplishing the same result is shown in Figs. 5 and 6, wherein the bores 2^b-3^b are drilled into the head 1^b from its rear end as previously described, and bores 10^b-11^b of respectively corresponding diameter are drilled into head 1^b from its front end, with the respective bores 2^b-10^b and 3^b-11^b preferably having axes which are parallel but so non-concentric that the respective bores 2^b and 10^b and 3^b and 11^b just fail to even partially overlap as shown in Fig. 6. Transverse bores 15-16 are drilled into head 1^b from its opposite sides so as to respectively open the bores 2^b-10^b and 3^b-11^b to one another along the lateral bores 15-16, and plugs 17 are then inserted in bores 15 and 16 so as to close the outer ends of said bores laterally beyond bores 2^b-3^b, thereby providing abruptly laterally offset paths of travel along the respective bores 10^b-15-2^b and 11^b-16-3^b, so that the transversely projecting abutment shoulders 12^b and 13^b which are formed in said laterally offset paths of travel will arrest rearward flame propagation as previously described.

The lateral offsets in the supply bores of the head of the torch may also form restrictions in said bores which will tend to stabilize flow of the gases to the mixer 4. Thus for example with the construction shown in Figs. 1 and 2, the partial overlapping of bores 2-10 and 3-11 reduces the cross-sectional areas of the flow of gases at the junction of bores 2-10 and 3-11 as shown in Fig. 2, and then immediately re-expands the cross-sectional areas of the flow to that which has prevailed throughout the lengths of bores 2-3; and with the construction shown in Figs. 3 and 4 the cross-sectional area of the

flow of acetylene is similarly reduced throughout the length of restricted bores 2^a, and is then re-expanded in bore 10^a to substantially that cross-sectional area of flow which is supplied through the acetylene tube 7. In similar manner the change in direction of the flow through the transverse bores 15 and 16 as provided for in the construction shown in Figs. 5 and 6, will act the same as restrictions in the cross-sectional area of the bores for the purpose of stabilizing the flow to the mixer.

The invention thus provides extremely simple but practical means for arresting flash-back in the supply bores which lead to the mixer of a torch, so that the arrested flame in either the acetylene or oxygen supply tube will be extinguished by the absence therein of the other component element necessary to form a combustible mixture, and the arrangement of the supply bores whereby they are adapted to arrest flash-back may also provide for stabilizing flow of the gases to the mixer in order to insure a combustible mixture of maximum efficiency.

I claim:

1. In a torch of the character described, a mixer, a head having a supply bore communicating with the mixer, the said bore having an abrupt lateral offset adapted to arrest flash-back rearwardly beyond the mixer and into said bore.

2. In a torch of the character described, a mixer, a head having a supply bore communicating with the mixer, the said bore having an abutment projecting into said bore and adapted for impingement by flame propagation rearwardly beyond the mixer and into said bore.

3. In a torch of the character described, a mixer, a head having a supply bore communicating with the mixer, the said bore having a restriction therein rearwardly from the mixer, with the cross-sectional area of said bore substantially the same in both directions beyond the restriction.

4. In a torch of the character described, a mixer, a head having a supply bore communicating with the mixer, the said bore having an abrupt lateral offset rearwardly from the mixer and forming an abutment projecting into said bore and adapted for impingement by flame propagation rearwardly beyond the mixer and into said bore.

5. In a torch of the character described, a mixer, a head having a supply bore communicating with the mixer, the said bore having an abrupt lateral offset forming a restriction in said bore rearwardly from the mixer, with said lateral offset adapted to arrest flash-back rearwardly beyond the mixer and into said bore.

6. In a torch of the character described, a mixer, a head having a supply bore communicating with the mixer, the said bore having

an abrupt lateral offset rearwardly from the mixer and forming an abutment projecting into said bore and adapted for impingement by flame propagation rearwardly beyond the mixer and into said bore, the abrupt lateral offset also forming a restriction in the said bore.

7. In a torch of the character described, a mixer, a head having bores for supplying a combustible gas and an oxidizing agent to the mixer, said bores each having an abrupt lateral offset adapted to arrest flash-back rearwardly beyond the mixer and into said bore.

8. In a torch of the character described, a mixer, a head having bores for supplying a combustible gas and an oxidizing agent to the mixer, said bores each having an abutment projecting into said bore and adapted for impingement by flame propagation rearwardly beyond the mixer and into said bore.

9. In a torch of the character described, a mixer, a head having bores for supplying a combustible gas and an oxidizing agent to the mixer, said bores each having a restriction therein rearwardly from the mixer.

10. In a torch of the character described, a mixer, a head having a supply bore communicating with the mixer, the said bore having the axis of its discharge end parallel to but so non-concentric with the axis of its supply end that said ends of the bore communicate by only a partial overlapping.

11. In a torch of the character described, a mixer, a head having bores for supplying a combustible gas and an oxidizing agent to the mixer, said bores each having the axis of its discharge end parallel to but so non-concentric with the axis of its supply end that said ends of the bore communicate by only a partial overlapping.

12. In a torch of the character described, walls forming a mixing chamber having communication with a burner, and walls forming a supply bore communicating with said mixing chamber, said bore having an abrupt lateral offset adapted to arrest flash-back rearwardly beyond the mixing chamber and into said bore.

13. In a torch of the character described, walls forming a mixing chamber having communication with a burner, and walls forming a supply bore communicating with said mixing chamber, said bore having an abutment projecting into said bore in a position to arrest flash-back in said bore.

14. In a torch of the character described, walls forming a mixing chamber having communication with a burner, and walls forming bores for supplying a combustible gas and an oxidizing agent to said mixing chamber, said bores each having an offset therein adapted to arrest flash-back rearwardly beyond the mixing chamber and into said bores.

15. In a torch of the character described,

walls forming a mixing chamber having communication with a burner, and walls forming bores for supplying a combustible gas and an oxidizing agent to said mixing chamber, said bores each having an abutment projecting thereinto for arresting flash-back therein.

16. In a torch of the character described, the combination of: a mixer; and a member having a supply passage communicating with said mixer, said supply passage including 10 two portions offset on a plane substantially normal to their axes for arresting flash-back.

17. In a torch of the character described, the combination of: a mixer; and walls forming 15 passages communicating with said mixer, at least one of said passages including two portions offset relative to each other and providing an abutment adapted for impeding flame propagation past said abutment.

18. In a torch of the character described, 20 the combination of: a mixer; a member having a supply passage communicating with said mixer; and an abutment attached to said member and extending into said passage substantially normal to the axis thereof for impeding flame propagation through said passage.

19. In a torch of the character described, the combination of: walls forming a mixing 30 chamber; and walls forming a combustion supporting gas passage and a combustible gas passage, said combustible gas passage including two portions offset to provide a shoulder adapted for impingement by flame propagation rearwardly beyond the mixing 35 chamber.

In testimony whereof I have affixed my signature.

ROY THOMAS.
